Chance Brothers and Co. Limited, Smethwick,
Birmingham, England

Application November 4, 1942, Serial No. 464,540
In Great Britain May 4, 1942

1 Claim. (Cl. 49—46)

This invention relates to electrically heated glass annealing kilns and particularly kilns for annealing optical glass.

The object of the present invention is to enable a more uniform temperature to be obtained in such a kiln than has hitherto been practicable.

The invention comprises the combination of a vertical chamber having a removable top cover, heating elements associated with the lateral, upper, and lower interior surfaces of the chamber, an air-circulating fan arranged in the lower part of the chamber, the base and cover of the chamber being shaped to present curved guiding surfaces to the air stream produced by the fan, glass-supporting means arranged within and spaced from the inner surfaces of the chamber, a vertical air passage extending axially through the glass-supporting means, and legs whereby the said means is supported on the base of the chamber.

The accompanying drawing is a sectional elevation of a glass annealing kiln embodying the invention.

In carrying the invention into effect as shown, we employ a vertical cylindrical chamber *a* having a removable top cover *b*, the side, base and removable top cover of this chamber being constructed from fireclay or other suitable refractory material. The inner faces of the side, base and removable top cover are suitably channelled to accommodate electrical heating elements *c* in the form of wires. The chamber *a* is contained in a metal or other casing *d* and the space between the chamber and casing may be packed with any convenient thermally insulating material as *e*. Moreover the top cover *b* is provided at its upper side with thermally insulating material *f* surrounded by a metal or other wall *g*.

The heating elements *c* associated with the underside of the cover *b* and/or base of the chamber *a* may be adapted to provide a sufficiently greater heating action than the other heating elements, to counteract any lack of uniformity of temperature in the chamber that might otherwise exist. The required relation between the different heating elements is determined by temperature exploration and once found is not subject to adjustment.

The glass pieces *h* to be annealed are carried by superimposed circular trays *i* supported by legs *j* on the base of the chamber *a*. The trays *i* are so constructed as to provide an axial vertical air passage *k* through the trays, and an annular

passage *m* between the peripheries of the trays and the inner vertical surface of the chamber *a*.

In the lower part of the chamber *a* is arranged an electrically driven centrifugal fan *n* for circulating the air in the chamber, the air stream produced by the fan being caused to flow up the annular passage *m* and down the axial passage *k*. To ensure uniformity of flow in all parts of the air stream the base and cover of the chamber *a* are suitably shaped to present curved guiding surfaces *o* to the stream.

By combining heating elements *c* with the base and cover as well as with the inner vertical surface of the chamber *a* we are able to obtain the desired uniform temperature within the chamber in a very satisfactory manner.

After the chamber *a* has been brought to the desired temperature the chamber and its contents are allowed to cool at a rate which can be determined by gradually diminishing the current supplied to heating elements *c*.

In the example shown the structure above described is supported by a metal or other base plate *p* on the upper ends of short pillars *q*, the base plate being thermally insulated from the base of the chamber *a*. On the underside of the base plate *p* is mounted an electric motor *r* and gearing *s* for driving the fan *n*. Further the top cover *b* is provided with lifting bolts *t*. and to minimise heat loss these bolts are embedded in the insulation *j*.

Whilst it is preferable to employ a cylindrical chamber, this is not essential, as the chamber may be of rectangular, or polygonal form.

Having thus described our invention what we claim as new and desire to secure by Letters Patent is:

A glass annealing kiln comprising the combination of a vertical chamber having a removable top cover, heating elements associated with the lateral, upper, and lower interior surfaces of the chamber, an air-circulating fan arranged in the lower part of the chamber, the base and cover of the chamber being shaped to present curved guiding surfaces to the air stream produced by the fan, glass-supporting means arranged within and spaced from the inner surfaces of the chamber, a vertical air passage extending axially through the glass-supporting means, and legs whereby the said means is supported on the base of the chamber.

WILLIAM NORMAN WHEAT,
REGINALD BULLOCK.
